Application May 10, 1935, Serial No. 20,810

9 Claims. (Cl. 40—5.2)

This invention relates generally to display apparatus and more particularly to a certain new and useful improvement in illuminated display signs of the revolving type.

Our invention has for its prime object the provision of a device or apparatus of the kind stated for producing a configurated path of flashing light in continuously changing visual patterns with luminous backgrounds, the whole being produced in a periodically varying degree of intensity and coloration of attention compelling display.

Our invention has for another object the provision of a sign of the type and for the purpose stated which may be economically constructed, which is automatic in actuation, and which contemplates the employment especially, though not exclusively, of gaseous glow tubes of the double electrode type, wherein the electrodes respectively glow or become luminescent when energized at alternate potentials from an alternating current source.

And with the above and other objects in view, our invention resides in the novel forms of form, construction, arrangement, and combination of parts presently described and pointed out in the claims.

In the accompanying drawings (three sheets),—

Figure 1 is a front elevational view of an illuminated rotary sign of our invention, parts thereof being broken away to show the interior construction;

Figure 2 is a rear view of the rotary frame-disc which carries the lamps or lights of the sign, other parts being omitted;

Figure 3 is a rear elevational view of the sign, the rear wall of the cabinet being removed;

Figure 4 is an enlarged detail view of one of the rotative lamps, taken approximately along the line 4—4, Figure 1;

Figure 5 is an enlarged detail fragmentary sectional view through another of the rotative lamps, taken approximately along the line 5—5, Figure 1;

Figure 6 is an enlarged fragmentary vertical sectional view through the upper half of the sign as illustrated in Figure 1, taken approximately along the line 6—6, Figure 1, with some parts omitted; and

Figure 7 is a diagrammatic representation of one of the visual patterns produced by the sign.

Referring now more in detail and by reference characters to the drawings, which illustrate a preferred embodiment of our invention, the sign-structure proper is preferably housed within a

box or cabinet A having a top-wall 1, bottom-wall or base 2, and side-walls 3, 4, respectively. At one upper corner of the box or shell A and connecting the walls 1, 3, is a diagonal brace 5, and at the diagonally opposite lower corner of the box A and similarly connecting the walls 2, 4, is a diagonal brace 6, as best seen in Figure 3.

The box A is also provided with a removable back-wall 8 and a front-wall 9, the latter having an enlarged annular sight-aperture 10 whose margins are preferably ornamentally scalloped, as at 11, as best seen in Figure 1.

At its larger end attached to the inside face, and embracing the aperture 10, of the front-wall 9 and having its smaller end presented rearwardly within the shell A, is a frusto-conical casing 12 forming a display-chamber B. At its inner or smaller end, the casing 12 has an annular flange 13 to which is marginally attached a preferably translucent disc 14, upon the outer 20 or front-face of which any particular sign, matter, or indicia may be displayed, as shown in Figure 1. The disc or sheet 14 forms the rear-wall of the chamber B, and suitable lamp-sockets 15, carrying or supporting any suitable preferably 25 electric lamps 16, are mounted on the respective braces 5, 6, for effecting trans-illumination of the sign-disc 14, as presently more particularly appears and as best seen in Figure 3.

Upstanding from the base or bottom-wall 2 of 30 the box A and disposed to the rear of the chamber B, is a standard or A-frame 17 terminating at its apex in a horizontally disposed hub or bearing 18, which partially projects forwardly into the chamber B through an aperture 19 provided for the purpose in the sign-disc 14, as seen in Figure 6.

Journalized in the bearing 18 and projecting at its opposite ends substantially therefrom, is a quill or rotatable sleeve 20, which, at its forward 40 end, carries an approximately rectangular hub-plate 21, as best seen in Figures 2 and 6. Intermediate the plate 21 and bearing 18, is first disposed a set-collar 22 and then a thrust-washer 23, the latter being preferably of insulation 45 material, as best seen in Figure 6.

On the rear end of the sleeve 20, is mounted a pulley 24, engaged by a belt 25, which extends to a pulley 26 on the shaft of a suitable prime-mover, as an electric-motor 27, mounted on the 50 bottom-wall 2 of the box A, as best seen in Figure 3.

Forming part of a frame C disposed for rotation in the chamber B and axially fixed to and upon the front face of the hub-plate 21 of 55

the sleeve 20, is a preferably insulation rear or main disc 28, and spaced forwardly in the chamber B from, and by means of spacer-elements 29 fixed in parallel relation to, the disc 28, is an also preferably insulation false front disc 30 preferably equipped with an axially disposed ornamental hub-cap 31, the discs 28, 30, being further provided with a plurality of registering radial stroboscopic openings or slots 32, in the present instance three in number, through which the sign-disc 14 is visually displayed in a stroboscopic manner on revolution of the frame C at a suitable speed, as will be readily understood, and as best seen in Figures 1, 2, and 6.

15 The main disc 28 of frame C carries a plurality of fixed or stationary lamp-sockets D, in the present instance five in number, disposed in any suitable or desired relative arrangement, one such arrangement being shown in Figures 1 and 2. Each socket D comprises a standard lamp-socket screw-base 33 of conducting material, whose side-wall forms one terminal of the socket, the base 33 having a conducting flange 34 and an insulation base 35 and the latter being provided with a contact button 36, forming the other terminal of the socket, in the usual manner. It may be observed that the disc 28 is provided with suitably threaded apertures 37, into and through which the respective sockets D are forwardly threaded or screwed until the respective flanges 34 engage the rear face of the disc 28 for securing the sockets in position.

30 The front disc 30 is provided with corresponding apertures 38, each in registration with a respective socket D, so as to permit respective glow-lamps E, presently to be more particularly described, to be inserted into the respective sockets D from the front side of the rotary frame C, as best seen in Figures 1 and 6.

40 The main disc 28 of frame C also carries a plurality of rotary sockets, in the present instance two in number, designated F, G, respectively, each of which comprises a metallic or conducting sleeve or barrel 39, in which is mounted a standard screw-base 40. The barrel 39 is mounted for rotation in a suitable aperture 41 provided in the disc 28 and is provided at one end with an annular flange 42, which engages the rear face of the disc 28, and at its other end with another annular flange or contact-ring 43, also of conducting material, which engages the front face of the disc 28.

45 Disposed on the disc 28 adjacent each respective socket F, G, is a bracket 44, on which is mounted a resilient conducting contact-finger or brush 45, whose free end has sliding contact with the periphery of the contact-ring 43 for forming one terminal of the socket F, or G, as the case may be, and as best seen in Figures 1, 4, and 5.

50 The other terminal of the socket F is formed by a resilient contact-finger 46 mounted on the rear face of the disc 28 and having its free end so suitably curved or arched as to clear the flange 42 for terminating at the axial center-line of the socket F, the fixed end of the finger 46 being conductively connected by a wire 47 with the hub-plate 21.

55 The other terminal of the socket G is provided by a similarly formed and disposed resilient contact-finger 48, which is, however, for convenience, conductively fixed at an end directly on the hub-plate 21, as best seen in Figure 2.

60 The front disc 30 is likewise suitably apertured for permitting glow-lamps E also to be inserted 70 from the front side of the frame C into the re-

spective sockets F, G, the usual contact knob 49 on the base of the respective lamp E then engaging the free end of contact finger 46 or 48, as the case may be, as best seen in Figure 5.

65 On the contact ring 43 of each socket F, G, 5 is mounted a gear 50, meshing with respective worms 51 mounted on the opposite ends of a shaft 52 extending diagonally across the front face of the rear disc 28, the shaft 52 being journaled suitably in and through the respective 10 brackets 44, as best seen in Figures 1, 4, and 5.

70 Intermediate its ends, the shaft 52 is also journaled in and through a bracket 53 disposed at the axis of the frame C, the shaft 52 there carrying a pinion 54 which meshes with a worm 55 15 mounted on a conducting stationary shaft 56 disposed in the axis of the frame C, and hence at right angles to the shaft 52. The shaft 56 is journaled also in and through the bracket 53 and extends axially through the sleeve 20, from 20 which the shaft 56 is electrically insulated, however, by means of an insulation bushing 57, the shaft 56 at its rear end projecting beyond the sleeve 20 into engagement with a bracket 58 attached to the rear box-wall 8 for securing the 25 shaft 56 against rotation, whereby, as the frame C is revolved, each respective socket F, G, is caused to rotate or whirl about an axis at right angles to its plane of circumvolution, as best seen in Figures 1 and 6.

30 Mounted conductively on the flange 42 of the socket G, is a distributor plate 59, which at its peripheral margin is provided with a plurality of radial contact fingers 60 adapted, when the socket G is rotated, as presently appearing, for effecting 35 intermittent engagement with an annular series of contacts 61, in the present instance five in number, mounted in and through the disc 28, and each conductively connected by respective wires 62, 63, 64, 65, 66, disposed on the front side 40 of the disc 28, with the respective flanges 34 of the sockets D. On the rear side of the disc 28, the contacts 36 of the sockets D are all conductively connected together by a loop-wire 67, which is, in turn, connected to the wire 47 and hence 45; also to the hub-plate 21, as best seen in Figures 1 and 2.

50 For supplying current to the circuit which effects incandescence of the electrodes of the several lamps E, a conventional type of electrical connection plug 68 is provided for connecting the apparatus to a suitable source of alternating current power supply (not shown), the plug 68 having a pair of flexible extension cords or leads 69, 70, respectively, which are passed in suitable 55 manner into the interior of the box A, as best seen in Figure 3.

55 One side of the circuit includes the lead 69, which is conductively connected to a terminal post 71 mounted on the bottom box-wall 2, and from the post 71, a lead 72 extends to the stationary shaft 56, to which the lead 72 is conductively connected, as at 73. This side of the circuit is then continued through the shaft 56, worm 55, pinion 54, and shaft 52, to each bracket 65 44, wiper 45, contact-ring 43, barrel 39, and finally the socket base 40 of the respective rotary sockets F, G.

60 In addition, the path of the circuit is continued through the distributor-plate 59 and its 70 fingers 60, contacts 61, and respective leads 62, 63, 64, 65, 66, to the flange 34 and socket-base 33 of the respective sockets D.

65 The return side of the circuit includes the 75 loop-wire 67, which connects the terminals 36

- of the respective sockets D and the contact finger 46 of the socket F, the latter, in turn, being connected through the lead 47 and the hub-plate 21 with the contact finger 48 of the socket G.
- 5 The circuit is then continued through the sleeve or quill 20 and bearing 18 to the standard 17, and the latter carries a terminal 74 to which the lead 70 is conductively connected, as best seen in Figure 3.
- 10 For effecting illumination of the lamps 16, a lead 15 extends from the terminal post 71 to one terminal of a thermo-electric type of intermittent or flasher switch 76 provided with a by-pass condenser 77 in the usual manner.

- 15 The other terminal of the switch 76 is preferably mounted directly on the one terminal of the socket 15 that is attached to the lower brace 6 of the box A, a lead 78 being extended from the switch 76 to one terminal of the other socket 20 15 that is attached to the upper brace 5.

- From the other terminal of the upper socket 15, a lead 79 extends to the corresponding terminal of the lower socket 15, and from thence a lead 80 extends to one side of an on-off switch 25 81 mounted in and through the wall 4 of the box A, the other side of the switch 81 being then connected by a lead 82 with the terminal 74 on the standard 17, as best seen in Figure 3.

- For supplying current to the motor 27, a lead 30 83 extends from the terminal post 71 to one side of the winding of the motor 27, the other side thereof being connected by a lead 84 to a terminal post 85 also on the standard 17. The terminal post 85 also serves to secure the terminal bracket of a by-pass condenser 86 to the standard 17, a lead 87 being extended from the condenser 86 to the post 71 for affording the customary condensive protection to the motor 27.

- 40 The lamps 16 are preferably of the customary type of electrical incandescent lamps for effecting transillumination of the sign 14.

- Our invention, however, is especially, though not exclusively, adapted to employ a glow-lamp E in the several sockets D, F, and G. Briefly, it 45 may here be said that the type of glow-lamp referred to comprises a light source having a periodically varying intensity and position of luminescence, and comprises a glass bulb or envelope 88, which contains a so-called rare gas, as neon, argon, or a mixture of similar gases, with a pair of metallic electrodes 89, 90, sealed within the bulb 88. The plates 89, 90, are in the form of opposing half-round sections, so that each plate 89, 90, is eccentrically disposed with 50 respect to the axis of the lamp, the bulb 88 preferably, though not necessarily, having a standard type of screw-base 91, as best seen in Figures 4 and 5.

- 60 When an alternating current is supplied to the lamp E, the respective electrodes 89, 90, will glow or become luminescent alternately, when each is on the negative half or alternation of a cycle of alternating current; for example, the electrode 89 glows when its potential is negative, while the electrode 90, being of opposite polarity 65 or positive, is dark, and vice-versa.

- 70 It follows that, if a lamp E is circumvolved or caused to move in a circular path, the respective electrodes 89, 90, will glow or rapidly flash with stroboscopic effect at successively spaced positions in the path of movement of the lamp, that is to say, each successive glow of an electrode will be angularly displaced with respect to 75 the preceding glow thereof, depending on the

speed of whirl of the lamp and the frequency of the applied alternating current.

When the rotative speed of the frame C is sufficiently high, the successive glow positions of a particular lamp E will be visually manifested by a pattern of light whose particular configuration will depend upon the relative orientation or angular position of the electrodes with respect to their circular path.

5 In some cases, for example, the glow may appear alternately on opposite sides of the path of circumvolution of the lamp, giving to the eye the effect of a series of disjoined arcuate wavy bands or streaks of light, as shown at 92 in Figure 7. Again, the glow may appear to the eye 15 as a series of disjoined irregular arcuate rectangles of light, as at 93 in Figure 7, and still other figures may be readily produced by mounting the lamps in selected position on the frame C.

Furthermore, when a lamp E is mounted in 20 one of the sockets F or G, the eccentrically disposed pair of electrodes 89, 90, are, in the manner described, caused to whirl about the axis of the lamp while the same is describing its path of circumvolution, whereby the visual pattern, as 92 or 93, produced by such lamp continually changes in shape and form, resulting 25 in the most beautiful and harmonious kaleidoscopic effects.

However, the bulb 88 may, if desired, be 30 sprayed or coated with a colored paint or like translucent material, which not only modifies the color of the light transmitted, but also effectively diffuses the light resulting from the rapid flashes of the electrodes 89, 90, so that such a 35 treated lamp, when revolved with the frame C, will give to the eye the effect of a broad circular band of diffused light, as at 94 or 95, in Figure 7, which, as in the present instance, forms an effective background to the more brilliant stroboscopic flashes from the uncoated or clear-bulb lamps.

40 In the present instance, several different kinds of glow lamps E are employed, which, for purposes of description, will be distinguished more 45 particularly by means of the series of lower case alphabetical reference characters a to g, inclusive.

The stroboscopic pattern 92 is produced by a clear bulb argon mixed gas or blue glow lamp a, 50 which is mounted in the whirling socket F. The background 94 is provided by three different colored lamps b, c, d, respectively, mounted in the outer three non-whirling sockets D. The lamp b is an argon blue glow lamp suitably sprayed so as 55 to give, for example, a diffused green light; the lamp c is a neon red glow lamp sprayed red, so as to give a diffused red light; and the lamp d is an argon blue glow lamp sprayed blue, so as to give a diffused blue light.

60 The stroboscopic pattern 93 is produced by a clear bulb neon red glow lamp e, which is mounted in the whirling socket G. The pattern 93 may be modified, however, by a super-positioned glow emitted from a clear-bulb neon red glow lamp f, 65 mounted in one of the inner two non-whirling sockets D. The background 95 is provided by an argon blue glow lamp g sprayed yellow, so as to give a green light.

70 Not all these lights are "on" at the same time. At the particular moment shown in the drawings, the whirling lamp a is producing the blue pattern 92, and the lamp c, being momentarily "on", is producing the red background 94, the lamps b and d being momentarily "off".

As the lamps *b*, *c*, and *d* are turned "off" and "on", singly or together, the color of the background 94 will change correspondingly, and as the lamp *a* is whirled, the pattern 92 will likewise 5 vary its form and shape, as has been previously set forth.

Similarly, the whirling lamp *e* is producing the red pattern 93, and the lamp *g*, being momentarily "on", is producing the green background 10 95, the lamp *f* being at the time momentarily "off". As the lamps *f* and *g* are turned "off" and "on", singly or together, the visual effect produced by the lamps *e*, *f*, and *g* will likewise vary in form, color, and shape.

15 During the operation of the device, the automatic thermo-switch 76 acts to intermittently energize the lamps 16 for effecting transillumination of the sign 14, which is then stroboscopically presented to vision through the rapidly moving slots 20 32 in the revolving frame C.

As desired, the manual switch 81 may also be employed for energizing or de-energizing the lamps 16 while the frame C is being revolved.

In practice, our invention provides a sign 25 wherein the most varied, beautiful, and unique effects may readily be produced, the revolving lights exhibiting attention compelling patterns of dazzling brilliancy in a constantly shifting or varying visual effect, the variations being both 30 in the colors displayed and in the details of the patterns shown as the display is revolved.

It will be understood that changes and modifications in the form, construction, arrangement, and combination of the several parts of our sign 35 35 may be made and substituted for those herein shown and described without departing from the nature and principle of our invention.

Having thus described our invention, what we claim and desire to secure by Letters Patent is,—

40 1. A sign comprising, in combination, a plurality of light-sources some of which having a periodically varying intensity and position of luminescence, means for intermittently deenergizing some of said light-sources, means for varying the 45 luminosity of said last-named light-sources, and means for circumvolving the light-sources in unison for impressing on the vision a configurated luminous pattern collectively formed by the several light-sources.

50 2. A sign comprising, in combination, a plurality of light-sources some of which having a periodically varying intensity and position of luminescence, means for circumvolving the light-sources in unison for impressing on the vision a 55 configurated luminous pattern produced by the periodically varying light-sources and comprising a back-ground formed by the remainder of the light-sources, means for rotating the periodically varying light-sources on their respective 60 axes while being circumvolved for effecting continuous variation in the pattern produced thereby, and means for varying the luminosity of the other light-sources for effecting variations in the luminous back-ground produced thereby.

65 3. A sign comprising, in combination, a light-

source having a periodically varying intensity and position of luminosity, a revolving frame supporting said light-source for effecting circumvolution thereof, and a display disposed rearwardly of the frame, the frame having series of openings therethrough for providing a stroboscopic view of the display through the frame.

4. A sign comprising, in combination, a light-source, a revolvable frame, a support for said light-source mounted for axial rotation on the 10 frame, means for rotating the frame, means for axially rotating said support relatively to the frame responsively to revolution of the frame, other light-sources also carried by the frame, and means responsive to axial rotation of said support 15 for effecting periodic illumination of the last-mentioned light-sources.

5. In a sign, a stationary translucent display, a stroboscopic frame mounted for rotation forwardly of the display, a plurality of light-sources carried by and movable with the frame, one of said light-sources being also and simultaneously axially movable relatively to the frame, and illuminating means disposed rearwardly of the display, said one light-source comprising a glow-tube 20 25 having electrodes respectively luminescent at alternate potentials.

6. In a sign, in combination, a lamp having electrodes respectively luminescent at alternate potentials, means for revolving the lamp bodily in 30 a circular path and simultaneously axially rotating the lamp, and means for supplying alternating current to the lamp during rotative movement thereof.

7. In a device of the character described, a 35 rotatable frame, a plurality of light-sources mounted in said frame, one of said light-sources being also rotatable about its own axis, and means co-operatively associated with the last-named light-source for completing electrical circuits to the various light-sources in a predetermined relationship.

8. In a device of the character described, a rotatable frame, a plurality of light-sources mounted in said frame, some of said light-sources 45 having a periodically varying intensity, one of said light-sources being also rotatable about its own axis, and means co-operatively associated with the last-named light source for completing electrical circuits to the various light-sources in 50 a predetermined relationship.

9. In a device of the character described, a rotatable frame, a plurality of light-sources mounted in said frame, one of said light-sources being also rotatable about its own axis, means co-operatively associated with the last-named light-source for completing electrical circuits to the various light-sources in a predetermined relationship for producing a light-patterned background, and stroboscopic means associated with 60 said frame for visually superimposing a predetermined light-pattern upon the background.

CURTIS O'CONNOR.
EDWARD LEE.
